(57) CLAIM

The ornamental design for a percussive massage gun, as shown and described.

DESCRIPTION

FIG. 1 is a front perspective view for a percussive massage gun showing my new design;

FIG. 2 is a back perspective view thereof;

FIG. 3 is a left side view thereof;

FIG. 4 is a right side view thereof;

FIG. 5 is a front view thereof;

FIG. 6 is a back view thereof;

FIG. 7 is a top plan view thereof; and,

FIG. 8 is a bottom plan view thereof.

The broken lines shown in the drawings are for the purpose of illustrating portions of the percussive massage gun, which form no part of the claimed design.

1 Claim, 8 Drawing Sheets(56)
